UNITED STATES PATENT OFFICE.

GEORGE P. JACKSON, OF FLUSHING, NEW YORK, ASSIGNOR TO INTERNATIONAL COMBUSTION ENGINEERING CORPORATION, OF NEW YORK, N. Y., A CORPORATION OF DELAWARE.

PULVERIZED-COAL-FEEDING DEVICE.

Application filed September 3, 1925. Serial No. 54,176.

This invention relates to devices for feeding pulverized coal and is especially useful in connection with the feeding of coal to the burners of a furnace such as used for example under stationary boilers.

The invention will be described as applied to a stationary boiler installation and its nature, objects and advantages will be best understood from the following:

- 10 In such installations it is customary to employ one or more bins for the pulverized coal, the bins being provided with a plurality of feeder devices from each of which an individual pipe leads to the burners of the furnace. Ordinarily all of these feeders are driven from a single shaft, suitable clutch mechanism being provided for each feeder. The feeders are cut in or cut out as may be needed to suit the requirements of firing.
- 20 I propose to split the feeders into units, each unit being driven by a motor which gives me a range of flexibility not otherwise securable although, of course, more motors are required. However, the advantage of increased flexibility more than compensates for the initial increase in investment for the following reasons. Certain of the feeders are operated more than the others and consequently these feeders wear more rapidly, in addition to which the wear, as between individual feeders, may vary. Since uniformity of feed is highly desirable in pulverized fuel burning installations, I am enabled by dividing up the feeders into units to meet these practical conditions which arise in service and secure a uniformity of feed.

I further propose to so arrange the connections from the feeders to the burners that I am enabled to obtain balanced flame conditions at various rates of operation and also at times when it may be necessary to shut down one or more of the motors for repairs.

How the foregoing, together with such other objects and advantages as may be incident to my invention, are realized, is illustrated in preferred form in the accompanying drawings, in which

Fig. 1 is a side elevation of my improved arrangement of feeding devices;

Fig. 2 is a similar view of a modification of my invention, and

Fig. 3 is a sectional view illustrating certain details of the invention.

Referring now to Fig. 1, the reference character 7 indicates the bin or bins beneath which are two feeding units A and B, these units comprising a suitable casing 8, each casing being provided with the feed screws 9, each of which is adapted to discharge into a pipe 10. In the present instance, each unit has four feed screws and each pipe 10 leads to a burner. Each unit is driven by a motor 11, the screws 9 being provided with worm wheels 12 adapted to engage worms 13 on the shafts 14. The shafts 14 may be coupled together by a clutch 15, whereby one motor may be utilized to drive both units.

The pipes 10 cross one another in the manner indicated in the figure so that each unit is adapted to feed every other burner of the row of burners C.

Normally each unit would be driven by its own motor and at low rates of firing one of the units would be cut out so that only half of the burners would be in operation. Inasmuch as when one of the units is cut out every alternate burner is cut out, it will be seen that a balanced flame condition must obtain in the furnace D. Thus at low ratings the balanced flame condition is obtained and a similar condition is obtained when it is necessary to shut down one of the units in order to make repairs in the feeder or feeders. If one of the motors should become defective, it can be repaired without disturbing the normal operation by simply coupling the two shafts 14 together.

Each feeder screw is controlled by a clutch 16 having an actuating lever 16^a so that individual feeders can be cut in or cut out to meet a wide range of variation in the rates at which the installation is being operated, in which connection it will, of course, be understood that the installation must be capable of being operated from a very low rating to a maximum or peak rating.

The arrangement shown in Fig. 2 is a refinement of the invention. Here there are four units F, each unit having two feeder screws and each unit being driven by a motor 17, each feeder screw being controlled by a clutch 16 as above. The pipes 18 leading from each feeder screw cross in the manner indicated. By cutting out the two middle units four burners only will be in operation and these will be in the middle, and a balanced flame condition will result. Fur-

thermore, the middle burners are utilized the most and hence the feeders which supply them wear the most rapidly and as they wear these feeders must be rotated more rapidly than the other feeders. Hence by splitting the feeders into a greater number of units this condition can be met by simply speeding up the motors operating such units. There is another advantage in splitting the feeders into a great number of units, namely, it is often desirable not to operate the end burners, i. e. those closest the side walls of the furnace, at as high a rate as the remaining burners, in order to prevent scouring of the side walls. The independent control which is afforded by splitting up the feeders into a large number of units makes it possible to take care of this condition by slowing down the motors for the feeders supplying the end burners, relative to the other motors. As before, a wide range of flexibility, in so far as variations in the rate of firing are concerned, is obtained by virtue of the fact that a feeder of each unit may be cut in or cut out as may be required for the particular rate at which the installation is being fed.

What I claim is:

1. In combination, a source of pulverized fuel supply, a plurality of feeders arranged in groups, means for independently operating the feeders of each group, a row of burners, pipes from feeders of a group to non-adjacent burners in the row, and pipes from the other feeders to the remaining burners.
2. In combination, a source of pulverized fuel supply, a plurality of feeders arranged in groups, means for independently operating the feeders of each group, a row of burners, pipes from feeders of a group to non-adjacent burners in the row, and pipes from the other feeders to the remaining burners, together with a clutch for each feeder.
3. In combination, a source of pulverized fuel supply, a plurality of feeders arranged in groups, means for independently operating the feeders of each group, a row of burners, pipes from feeders of a group to non-adjacent burners in the row, and pipes from the other feeders to the remaining burners, together with a clutch for each feeder, and

means whereby all feeders may be driven from the same source.

4. In combination, a source of powdered fuel supply, a plurality of feeders arranged in groups and taking fuel from said source, independent means for operating the feeders of each group, a row of burners, and connecting means between each feeder and a burner, one or more burners fed by a feeder of one particular group being positioned between burners fed by feeders not of that group.

5. In combination, a source of powdered fuel supply, a plurality of feeders arranged in groups and taking fuel from said source, independent means for operating the feeders of each group, a row of burners, and connecting means between each feeder and a burner, one or more burners fed by a feeder of one particular group being positioned between burners fed by feeders not of that group, together with means for causing the operating means of one group to operate more than one group.

6. In combination, a source of powdered fuel supply, a plurality of feeders arranged in groups and taking fuel from said source, independent means for operating the feeders of each group, a row of burners, and connecting means between each feeder and a burner, one or more burners fed by a feeder of one particular group being positioned between burners fed by feeders not of that group, together with means for rendering individual feeders inoperative.

7. In combination, a source of powdered fuel supply, a plurality of feeders arranged in groups and taking fuel from said source, independent means for operating the feeders of each group, a row of burners, and connecting means between each feeder and a burner, one or more burners fed by a feeder of one particular group being positioned between burners fed by feeders not of that group, together with means for causing the operating means of one group to operate more than one group and means for rendering individual feeders inoperative.

In testimony whereof, I have hereunto signed my name.

GEORGE P. JACKSON.
